UNITED STATES PATENT OFFICE.

WALTER O. SNELLING, OF ALLEN TOWN, PENNSYLVANIA, ASSIGNOR TO TROJAN POWDER COMPANY, OF NEW YORK, N. Y., A CORPORATION OF NEW YORK.

EXPLOSIVE AND METHOD OF MANUFACTURING SAME.

1,395,775.

Specification of Letters Patent.

Patented Nov. 1, 1921.

No Drawing.

Application filed March 25, 1920. Serial No. 368,606.

To all whom it may concern:

Be it known that I, WALTER O. SNELLING, a citizen of the United States, and resident of Allentown, Lehigh county, Pennsylvania, have invented certain Improvements in Explosives and Methods of Manufacturing Same, of which the following is a specification.

My invention relates to new and improved explosives of the detonating type, and more particularly has to do with explosives in which there is present an inorganic nitrate in close association with a material which, although non-explosive in itself, is capable 10 of reacting explosively with the nitrate under certain conditions, and particularly when a finely divided solid detonating explosive is present as an additional sensitizing agent.

The desirability of utilizing inorganic 20 nitrates, such for example as ammonium nitrate, as the major ingredient of an explosive mixture, is quite apparent to the explosive chemist, but the matter of properly sensitizing such materials has presented 25 some difficulty. I have discovered that an inorganic nitrate may be partially sensitized by providing it with a coating of an organic material which is not in itself explosive, and the partially sensitized nitrate 30 may then be completely sensitized by admixture with particles of a solid organic nitrate.

For purposes of illustration I will describe 35 an embodiment of my invention in which the inorganic nitrate employed is ammonium nitrate, the non-explosive sensitizing agent is vulcanized or sulfurized oil, and the solid organic nitrate is nitrostarch.

I first take ammonium nitrate particles of 40 proper grain size, and coat these particles, preferably under continued agitation or stirring, by means of a vulcanizable oil, such as cottonseed oil, for example. When each particle of the ammonium nitrate or 45 other nitrate to be coated, has received a proper coating of the vulcanizable oil, I contact the particles with a vulcanizing agent such as the vapor of sulfur chlorid. I may of course use a vulcanizable oil and sulfur 50 and bring about vulcanization by the use of a suitable temperature, but the method described gives very desirable results without the use of any artificially applied heat. Under the influence of the vulcanizing agent the 55 liquid oil on the particles of the nitrate be-

comes rapidly solidified, and for reasons not known to me becomes remarkably efficient as a sensitizing agent in the presence of a solid detonating agent such as nitrostarch or equivalent primary explosive material. 60

For the purpose of removing excess sulfur chlorid, and neutralizing any acidity which may be caused by the vulcanizing reaction, I may, after blowing sulfur chlorid vapors through the mass of coated nitrate particles, 65 blow air through the mass for a period and then blow dilute ammonia vapors for an additional period.

By mixing the coated and partially sensitized ammonium nitrate particles with suitable proportions of nitrostarch I secure 70 valuable explosives. The preferred proportions of the several ingredients are from 3% to 15% of nitrostarch to 97% to 85% of coated ammonium nitrate, the oil coating 75 representing from 1 to 10% of the coated nitrate.

Instead of obtaining the solid non-explosive sensitizing coating on particles of a nitrate in the manner described, I may obtain 80 such a coating by other means not involving vulcanization, but producing the same result of transforming a liquid coating first applied into a solid firmly adhering coating. I may for example agitate my 85 particles of nitrate with liquid tung oil, or with equivalent oil which polymerizes to a solid body on an exposure to an elevated temperature, and having applied such coating of liquid oil I may then raise the temperature, 90 and polymerize the oil to a solid non-explosive sensitizing coating. By another alternative method I may coat my 95 nitrate particles at an elevated temperature by means of a liquid oil or resin maintained liquid by the elevated temperature employed, and I may then cause the liquid coating so applied to solidify by allowing the 100 temperature of the coated particles to fall. By still another alternative method I may 105 coat my particles of ammonium nitrate with a liquid oil which becomes changed to a solid through other influences than vulcanization or polymerization by heat. I may for example coat my particles with a drying oil, 110 with or without the presence of a drier, and I may then blow air or oxygen, or other chemical agent through the mass, or otherwise contact the particles coated with the liquid oil so as to cause the liquid to oxidize 110

or otherwise be chemically changed into its solid reaction product. By coating nitrate particles with linseed oil for example, with or without the presence of a metallic or organic drier, and by then blowing air through the mass while agitating the same, and preferably by maintaining the temperature sufficiently above normal to accelerate the reaction, I obtain a solid coating of solidified linseed oil which is well adapted to my use as a non-explosive solid sensitizing agent. As equivalent for the sensitizing or partially sensitizing agents specifically mentioned I may use other non-explosive solid organic coating materials high in carbon and hydrogen, causing the same to closely adhere to the particles of inorganic nitrate by application as a liquid and subsequent transformation by chemical or physical means to the form of a solid.

The range of inorganic nitrates available as equivalent for ammonium nitrate is large. For example I may employ sodium nitrate, potassium nitrate, or barium nitrate, either alone, or in admixture with ammonium nitrate, or in admixture with each other, with or without the presence of ammonium nitrate; and I find in general that a large number of inorganic nitrates, when sensitized by means of a non-explosive, solid, closely adhering organic body of relatively high carbon and hydrogen content, become capable of use in combination with a solid detonating agent as explosives of great strength and high efficiency. As equivalents of nitrated starch, I may use nitrated cellulose or other solid nitrated carbohydrates, such as the solid nitrated sugars, or other explosive materials, of solid nature existing as distinct solid particles capable of detonation, and capable of transmitting detonation from one particle to another.

I claim:

1. An explosive composition comprising an inorganic nitrate coated with a closely-adhering solidified non-explosive sensitizing agent and mixed with sufficient of a solid explosive sensitizing agent to render the whole sensitive to detonation.
2. An explosive composition containing an inorganic nitrate coated with a solid non-explosive vulcanized oil.
3. An explosive composition comprising an inorganic nitrate coated with a solid non-explosive vulcanized oil and sensitized by admixture with a solid detonating explosive.
4. An explosive composition comprising an inorganic nitrate coated with a solid non-explosive polymerized oil and sensitized by admixture with a solid detonating explosive.
5. An explosive composition comprising an inorganic nitrate coated with a solid non-explosive oxidized oil and sensitized by admixture with a solid detonating explosive.

6. An explosive composition containing ammonium nitrate particles provided with a closely adhering coating of a non-explosive oil solidified by sulfurization.

7. An explosive composition comprising ammonium nitrate particles provided with a closely adhering coating of a non-explosive oil solidified by sulfurization and mixed with a solid inorganic nitrate.

8. An explosive composition comprising 85% to 97% ammonium nitrate particles coated with a non-explosive solidified oil, and 15% to 3% nitrostarch.

9. In the manufacture of explosives, the process which comprises coating particles of an inorganic nitrate with a thin layer of a liquid, non-explosive sensitizing agent, transforming such liquid non-explosive sensitizing agent to solid condition, and admixing sufficient solid explosive sensitizing agent to render the whole sufficiently sensitive to detonation.

10. In the manufacture of explosives, the process which comprises coating particles of an inorganic nitrate with a thin layer of a non-explosive liquid, transforming such liquid to a solid so as to obtain a closely adhering solid coating of non-explosive nature on the particles of inorganic nitrate, and admixing sufficient solid explosive sensitizing agent to the coated particles so obtained as to render them sensitive to detonation from a fulminate cap containing one gram of mercury fulminate.

11. In the manufacture of explosives, the process which comprises coating particles of an inorganic nitrate with a thin layer of a liquid, non-explosive oil, transforming such oil to solid condition by the action of a vulcanizing agent, and admixing sufficient solid explosive sensitizing agent to render the whole sufficiently sensitive to detonation.

12. Sensitizing an inorganic nitrate by coating particles thereof with a thin layer of a liquid non-explosive oil and solidifying said oil by contact with a vaporous vulcanizing agent.

13. Sensitizing an inorganic nitrate by coating particles thereof with a non-explosive oil in liquid form and polymerizing said coating to a solid body by heat.

14. Sensitizing an inorganic nitrate by coating particles thereof with liquid tung oil and polymerizing said coating to a solid body by heat.

15. The method of manufacturing explosives which consists in incompletely sensitizing ammonium nitrate by providing particles thereof with a thin coating of non-explosive liquid oil and solidifying said coating, and adding sufficient nitrostarch to completely sensitize the entire mixture.

16. The method of forming an explosive which consists of coating particles of ammonium nitrate with sufficient of sensitiz-

ing material to incompletely sensitize said nitrate, and admixing with said incompletely sensitized particles, sufficient of a detonating agent to completely sensitize the entire mass.

17. The method of forming an explosive which consists of coating particles of am-

monium nitrate with sufficient of a sensitizing material to incompletely sensitize said nitrate, and admixing with said incompletely sensitized particles sufficient nitrostarch to completely sensitize the entire mass.

WALTER O. SNELLING.
